Attorney, Agent, or Firm—Andrus, Sceales, Starke & Sawall[57] **CLAIM**

The ornamental design for a combined cap and face mask, as shown and described.

DESCRIPTION

FIG. 1 is a front perspective view of a combined cap and face mask showing my new design;

FIG. 2 is a left side elevational view thereof, the right side being a mirror image;

FIG. 3 is a top plan view thereof;

FIG. 4 is a bottom plan view thereof;

FIG. 5 is a front elevational view thereof; and,

FIG. 6 is a rear elevational view thereof.

The crosshatch shading shown in all view is understood to repeat throughout the indicated area. The mouthguard shown in broken lines in FIG. 1 is for illustrative purposes only and forms no part of the claimed design.
